UNITED STATES PATENT OFFICE.

JOSEPH EKSTEIN, OF NEW YORK, N. Y.

DESIGN FOR A WHEELED TOY.

Application filed November 17, 1927. Serial No. 24,196. Term of patent 3½ years.

To all whom it may concern:

Be it known that I, JOSEPH EKSTEIN, a citizen of the United States, residing in the borough of Manhattan, city, county, and State of New York, have invented a new, original, and ornamental Design for a Wheeled Toy, of which the following is a specification, reference being had to the accompanying drawing, forming part thereof.

The figure is a perspective view of a wheeled toy showing my new design.

I claim:

The ornamental design for a wheeled toy as shown.

In testimony whereof I have affixed my signature to this specification.

JOSEPH EKSTEIN.
